PORTABLE SHELTER FOR AUTOMOBILES

Samuel Mitchell and Adam Guidry, Vallejo, Calif.

Application January 12, 1950, Serial No. 138,198

8 Claims. (Cl. 135—4)

1

This invention relates to weather shields for the protective covering of automobiles and the like.

An object of the invention is to provide a portable shroud, composed of flexible and preferably waterproof material such as treated fabric or sheet plastic, capable of covering a sizeable object such as an automobile and having supporting means associated therewith designed to maintain the hood in proper form and away from actual contact with the surface of the covered object.

Another object of the invention is to provide a combined frame and sheet material shelter which is capable of being rapidly set up or dismantled.

A further object of the invention is to provide a device of the character described arranged to be folded into a very compact bundle of such overall dimensions as will permit ready accommodation thereof in the luggage compartment of the average automobile.

Still another object of the invention is to provide a device of the type referred to which although of lightweight construction is sufficiently sturdy to withstand abnormally rough handling without suffering severe damage, and which is capable of being easily set up or dismantled by a person without the need of additional help.

Yet another object of the invention is to provide apparatus of the class described which has been simplified to the point wherein it may be manufactured and sold very economically.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawing and description may be adopted within the scope of the invention as set forth in the claims.

Referring to the drawings:

Figure 1 is a side elevational view of the portable shelter of our invention with parts broken away so as to show details of the supporting frame.

Figure 2 is a vertical sectional view taken in the plane indicated by the line 2—2 of Figure 1.

Figure 3 is a view similar to Figure 2 showing the frame in collapsed condition for storage.

Figure 4 is an enlarged sectional view of the upper section of the frame bows showing the folding pivots therefor.

2

Figure 5 is an enlarged portional side elevational view of the lower pivot for the frame bows.

Figure 6 is a perspective view of a frame bow unit showing the latter in operative condition.

It is well known that the original color and surface sheen of an automobile, unless the latter is adequately protected against the weathering and oxidizing actions of sun, wind and rain, will rapidly deteriorate so that the initial beauty of the vehicle is lost and the value of the latter is materially depreciated. Carelessness is not the main factor underlying the comparatively shabby appearance of many automobiles since, in a large number of cases, the latter's owners are unable to successfully combat the conditions responsible for such deterioration. In many residential districts there exists an inadequate supply of garage space which necessitates that many surplus vehicles have to be left outdoors and exposed to all sorts of weather conditions. In other cases, even though the provision is made to properly house the vehicle during night hours, the former may be required to transport the owner to and from his place of employment and is most usually left exposed throughout the day to the aforesaid weathering conditions in addition to the finish-destroying actions of industrial smoke and fumes or the corrosive influence of salt laden mist or spray if the vehicle is located adjacent the seashore or a bay tributary to the ocean. It is obvious under such circumstances that in order to maintain a vehicle's finish in prime condition, a person would be required to expend considerable time each day in removing surface dust and stains and in applying wax or other preservative to the body surfaces and trim.

We have developed a simple and efficient portable shelter, for vehicles which must be left exposed to the weather for extended periods of time, which is capable of being rapidly set up to enclose the vehicle and which, after serving its purpose, may be readily dismantled and stored in the vehicle's luggage compartment. As here shown, a pair of support frame units is provided each of which comprises a main U-shaped bow member 8 constructed of light gauge angle or channel bar or cylindrical tubing to which is pivotally attached one or preferably two similarly shaped bow members 9 and 11. Details of the pivotal connection between the members 8, 9 and 11 are shown in Figure 5 wherein it will be seen that the vertical side posts 12 of the bow member 8 are provided adjacent their lower ends with pivot pins 13 on which are journaled the side wings 14 of a sheet metal pivot bracket 16 con-

nected in a central portion thereof by means of rivets 17 or by spot-welding to the arm portions 18 of the bow member 9, the oppositely extending side wings 19 of the pivot bracket being engaged with the ends of the arm portions 21 of the bow member 11 by means of pivot pins 22. The arrangement of the parts and the disposition of the pivot pins 13 and 22 are such that each and both of the bow members 9 and 11 are capable of being swung upwardly to positions alongside of the bow member 8 from their lowered and extended positions shown in Figures 1 and 2. This, as will be later explained, facilitates folding of the device into a compact bundle for storage. It will be noted that the end portions of the arm members 18 and 21 are so formed and related to the pivot pins 13 and 22 that when the bow members 9 and 11 are in the lowered and extended positions relative to the bow member 8, a transverse end surface 23 of the arm member 18 will abut against the adjacent vertical face of the arm member 12 while the side and end surfaces 24 and 26 of the arm member 21 will abut respectively against the end surface 27 of the member 18, which corresponds to the surface 23, and against the aforesaid adjacent vertical face of the arm member 12. Thus positive stops are provided which limit the downward swing of each of the arms 9 and 11 relative to the main supporting member 8. The bottoms of the side posts 12 are provided with supporting feet 28 here shown as comprising short sections of material equivalent to that used in the side posts which are connected by hinges 29 to swing from their normally horizontal positions at right angles to the side posts to folded positions lying adjacent the vertical face of the side posts. Brace members 31 are provided preferably comprising metal bars connected at one end to the feet 28 by pivot pins 32 and having laterally opening notches at the opposite end adapted to releasably engage suitable anchor studs 33 provided on the side posts 12.

As will be seen, particularly in Figure 3, each end frame unit comprising the conjoined bow members 8, 9 and 11 is foldable so as to reduce the units to compact bundles of such minimized bulk as will permit their ready storage in limited space such as the luggage compartment of an automobile. As here shown, hinges 34 are provided at the junctions of the straight arm portions 12, 18 and 21 of each of the bow frames with the separate arched transverse sections 36 thereof, each of the latter sections having hinges 37 disposed medially of the ends thereof. The hinges 34 and 37 are arranged to permit relatively inward folding of the straight arm portions of the bow frames and also of the arched sections of the frames and the arrangement is also such that when the frames 8, 9 and 11 are brought into relative parallelism, the pintles of corresponding hinges 34 and 37 will be axially aligned so as to permit the simultaneous folding without binding of all of the bow members comprising an individual end support frame. This latter folding may be accomplished by first collapsing the extended supporting feet 28, swinging the straight side post portions of the frames relatively inwardly about the hinges 34 to lie adjacent the arched top sections of the frames and thereafter folding the latter relatively toward each other about the hinges 37. This forms the compact bundle in which the support frame is shown in Figure 4.

In use, the pair of support frames are erected 75

at opposite ends of the automobile 38 to be sheltered and are suitably held fixedly in position. As here shown such positioning means for the frames may comprise loops of flexible wire cable 39 arranged in vertically spaced horizontal runs extending between upper and lower portions of the relatively spaced posts 12 of the frames and having convergent ends 41 which may be engaged with stakes 42 or other suitable anchoring means driven into the ground or otherwise disposed forwardly and rearwardly of the automobile 38. It is preferred that, as shown in Figure 4, at least one and preferably both of the runs of the guy cables 39 be fixedly attached to the posts 12, such as by weaving a portion of the cable around and between the spaced peg members 43 carried by and extending from the inner faces of the posts 12, and that a turnbuckle 44 or its functional equivalent be provided in each cable loop so as to draw the latter desirably taut. Additional lengths of cable 46 are provided which extend between the arched portions of the main support frames and are preferably releasably attached to the latter at their ends so as to permit detachment and separate storage of the cables together with the guy cable loops when the support frames are taken down and folded.

Means are provided which are detachably engageable with the respective bow members of the support frames and which comprise a protective covering for the automobile 38. As here shown each of the bow frame members and the main support frames including the side posts 12, are provided with snap fasteners 47 which are substantially uniformly relatively spaced and extend entirely along the outer surface of each member of the end support frames between the opposite pivot hinges which permit folding of the frames along the longitudinal plane of the shelter unit. 40 A main cover sheet 48 composed of waterproof fabric, flexible sheet plastic or the like is provided which is laid transversely across the shelter support substructure and is provided along opposite edges with fastener elements complementary and engageable with the snap fasteners 47 so as to attach the sheet 48 between the main frame including the posts 12 and bow members 36, the transverse length of the sheet 48 being such that the opposite edges 49 of the latter are disposed only an inch or so above the surface of the ground. Cover sheets 51 are also provided extending between the angularly-disposed bow members of the end support frames the lowermost sheets 51 preferably having skirt portions 52 which extend downwardly to terminate just above the surface of the ground. If desired the cover sheets 51 may be made as separate units or they may be combined to form single cover elements connectible as units to their respective end support frames.

60 The structure of our invention above described is comparatively simple in design which renders it capable of being easily handled and set up by a single person with little difficulty, which affords the maximum of protection for the sheltered automobile against the damaging effects of dust, rain or corrosive industrial fumes and which may be readily dismantled and reduced to a bundle of such compactness as to permit its convenient storage in a restricted volumetric space such as exists in the luggage compartment of a vehicle. It will be seen furthermore that the simplicity of design renders the shelter capable of being manufactured to sell at a cost which will not be prohibitive to the average buyer.

We claim:

1. A portable shelter for automobiles and the like comprising demountable relatively spaced ground-engaging main frames of normally U-shaped form disposed intermediate the ends of and straddling said automobile, correspondingly shaped bow frames carried by said main frames and extending therefrom to overlie extreme end portions of said automobile, guy members interconnecting certain of said frames and the ground for fixedly positioning the main frames relative to each other and to the ground, and sections of sheet material overlying and secured to said main and bow frames and covering said automobile.

2. A portable shelter for automobiles and the like comprising demountable relatively spaced ground-engaging main frames of normally U-shaped form disposed intermediate the ends of and straddling said automobile, correspondingly shaped bow frames pivotally engaged with said main frame and movable from positions substantially parallel with the latter to positions extending angularly therefrom to overlie extreme end portions of said automobile, guy members interconnecting certain of said frames and the ground for fixedly positioning the main frames relative to each other and to the ground, and sections of sheet material overlying and secured to said main and bow frames and covering said automobile.

3. A portable shelter for automobiles and the like, comprising demountable relatively spaced ground-engaging main frames of normally U-shaped form disposed intermediate the ends of and straddling said automobile, correspondingly shaped bow frames pivotally engaged with said main frame and movable from positions substantially parallel with the latter to positions extending angularly therefrom to overlie extreme end portions of said automobile, means cooperative between portions of said main and bow frames for prescribing the degree of angularity between the latter and the main frames, guy members interconnecting certain of said frames for fixedly positioning the main frame relative to each other, and sections of sheet material overlying and secured to said main and bow frames and covering said automobile.

4. A portable shelter for automobiles and the like comprising demountable relatively spaced ground-engaging main frames of normally U-shaped form disposed intermediate the ends of and straddling said automobile, correspondingly shaped bow frames carried by said main frames and extending therefrom to overlie extreme end portions of said automobile, guy members interconnecting certain of said frames and the ground for fixedly positioning the main frames relative to each other and to the ground, fastener elements secured to and extending from at least a pair of relatively spaced frames, and sheet material overlying said main and bow frames and connected with said fasteners, said sheet material covering said automobile.

5. A portable shelter for automobiles and the like, comprising separate relatively spaced ground-engaging main frames of normally U-shaped form disposed intermediate the ends of and straddling said automobile, correspondingly shaped bow frames pivotally engaged with said main frame and movable from positions substantially parallel with the latter to positions extending angularly therefrom to overlie extreme end portions of said automobile, detachable guy

members interconnecting certain of said frames and the ground for fixedly positioning the main frames relative to each other and to the ground, sheet material overlying and detachably secured to said frames and covering said automobile, and said main and bow frames when in relatively parallel positions being foldable upon themselves to reduce the frames to compact bundles.

6. A portable shelter for automobiles and the like comprising separate relatively spaced ground-engaging main frames of normally U-shaped form disposed intermediate the ends of and straddling said automobile, said main frames comprising relatively spaced vertically-extending post members arranged at opposite sides of said automobile and an arched top member pivotally engaged with upper end portions of said post members and extending transversely above said automobile, substantially U-shaped bow frames extending from said main frames and movable from positions substantially parallel with the latter to positions extending angularly therefrom to overlie extreme end portions of said automobile, said bow frames each comprising arm members pivotally connected with said main frame post members and further comprising bow members pivotally engaged with outer end portions of said arm members, detachable guy members interconnecting certain of said frames and secured to the ground for fixedly positioning the main frames relative to each other and to the ground, sheet material overlying and detachably secured to said frames and covering said automobile and said main and bow frames when in their aforesaid relatively parallel positions being foldable about the pivotal connections of the arched top member with the arm members respectively to reduce the frames to compact bundles.

7. A portable shelter for automobiles and the like comprising separate relatively spaced ground-engaging main frames of normally U-shaped form disposed intermediate the ends of and straddling said automobile, said main frames comprising relatively spaced vertically-extending post members arranged at opposite sides of said automobile and an arched top member pivotally engaged with upper end portions of said post members and extending transversely above said automobile, substantially U-shaped bow frames extending from said main frames and movable from positions substantially parallel with the latter to positions extending angularly therefrom to overlie extreme end portions of said automobile, said bow frames each comprising arm members pivotally connected with said main frame post members and further comprising bow members pivotally engaged with outer end portions of said arm members, detachable guy members each comprising lengths of flexible cable formed in loops extending along opposite sides of said automobile, said loops each having parallel rims detachably engaged with said main frames adjacent the top and bottom portions of the post members thereof, said loops further having end portions thereof attached to the ground at points adjacent the ends of said automobile, sheet material overlying and detachably secured to said frames and covering said automobile and said main and bow frames when in their aforesaid relatively parallel positions being foldable about the pivotal connections of the arched top member with the post members and the bow members with the arm members respectively to reduce the frames to compact bundles.

8. A portable shelter for automobiles and the like comprising separate relatively spaced ground-engaging main frames of normally U-shaped form disposed intermediate the ends of and straddling said automobile, said main frames comprising relatively spaced vertically-extending post members arranged at opposite sides of said automobile and an arched top member pivotally engaged with upper end portions of said post members and extending transversely above said automobile, substantially U-shaped bow frames extending from said main frames and movable from positions substantially parallel with the latter to positions extending angularly therefrom to overlie extreme end portions of said automobile, said bow frames each comprising arm members pivotally connected with said main frame post members and further comprising bow members pivotally engaged with outer end portions of said arm members, means carried by the arm members of said bow frames engageable with said post members when the bow frames are in extended positions for establishing prescribed degrees of angularity between the bow frames and post members, detachable guy members inter- 25

connecting certain of said frames and secured to the ground for fixedly positioning the main frames relative to each other and to the ground, sheet material overlying and detachably secured to said frames and covering said automobile and said main and bow frames when in their aforesaid relatively parallel positions being foldable about the pivotal connections of the arched top member with the post members and the bow members with the arm members respectively to reduce the frames to compact bundles.
